UNITED STATES PATENT OFFICE

MORRIS W. GREENSTEIN, OF NEW YORK, N. Y.

DESIGN FOR AN APPLIQUE GINGHAM EFFECT CHINTZ

Application filed April 2, 1932. Serial No. 43,375. Term of patent 3½ years.

To all whom it may concern:

Be it known that MORRIS W. GREENSTEIN, a citizen of the United States, residing in New York, in the county and State of New York, has invented a new, original, and ornamental Design for an Applique Gingham Effect Chintz, of which the following is a specification, reference being had to the accompanying drawing, forming a part thereof.

The figure of the drawing shows a plan view of a piece of chintz embodying my design, a complete repeatable unit being in-

cluded within the arrow indications. The horizontal marginal lines represent the selvage edges or the width of the material.

The lines at the upper left hand corner of the drawing indicate the gingham background which is continued over the surface of the fabric forming the background.

I claim:—

The ornamental design for an applique gingham effect chintz substantially as shown and described.

MORRIS W. GREENSTEIN.
